7 Claims. (Cl. 196—53)

This invention relates to a method of releasing the pressure of mixtures of solids and liquids existing at high pressures, and the principal object is to provide a system whereby the wear and tear on reducing valves is avoided. Particularly when a solid of abrasive character, such as iron oxide, is present in the mixture the consequential erosion of valve parts is a very serious matter. The invention is especially applicable to the release of pressure on mixtures of powdered coal and oil from a destructive hydrogenation process, with or without other solid materials of an inert or catalytic character. A subsidiary object of the invention is to provide a system whereby a large proportion of the potential energy of the high-pressure mixture is recovered as useful external work.

According to the invention, the pressure of the liquid-solid mixture is transferred to a fluid, preferably a liquid, whose pressure can then be released in any known manner without difficulty since erosion does not occur to such a serious extent in absence of solid matter. The transfer of pressure can be effected by the aid of slowly moving parts or without the necessity of constricted passages liable to erosion.

In the preferred form of the invention the pressure on the mixture is released in a cylinder ram the piston of which is balanced by the pressure of an auxiliary liquid such as water or oil contained in a second cylinder, the admission and exhaust of mixture and auxiliary liquid respectively being controlled to ensure a slow movement. The mixture from which the pressure has been released is then expelled from the cylinder of the ram by the return stroke of the piston.

The invention is illustrated in the accompanying diagram. In the figure a mixture of solid and liquid is withdrawn from a high-pressure vessel 1 and it is required to release the pressure on the mixture. The mixture is allowed to pass through a pipe 2 to the cylinder 4 of the ram 5. The piston 6 of the ram acts also in the cylinder 11 of a second ram 10, and reciprocates between the two rams in accordance with the positions of the valves 3, 7, 12 and 13, which control the inlet and outlet of mixture and of auxiliary fluid to the respective cylinders. These valves except valve 3 open and close only when the piston 6 is stationary, i. e. when there is no movement of mixture or of liquid through the connecting pipes. The valve controller may be of the type described in British specification 55 No. 282,505 in which cams on a timing shaft

actuate periodically pilot valves. The ram may conveniently be of greater area in the auxiliary liquid cylinder as shown.

The exit pipe 8 for mixture leads to a low-pressure storage vessel 9. The inlet pipe 15 for auxiliary liquid i. e. liquid to which the pressure is transferred is supplied with liquid at a few atmospheres pressure by the accumulator 14 of the ordinary weight loaded type and pump 18. The exit pipe 16 for auxiliary liquid is provided with a variable orifice 17 to control the outlet of liquid and hence the rate of movement of the piston 6 and the rate of admission of mixture into the cylinder 4. The auxiliary liquid at high pressure passes to the accumulator 19 and is utilized in any known manner for the recovery of its energy; its pressure can be released without inconvenience as it contains no solid matter, for example in the motor 20.

The working of the system is as follows. The piston 6 being at the top of its stroke, the valve 7 is shut and the valve 3 opened. Simultaneously valve 12 is shut and valve 13 opened, and the pressure of the mixture in the cylinder 4 will cause the piston to fall and expel the auxiliary liquid through the orifice 17 and the pipe 16. Valve 3 is preferably shut before the piston has reached the opposite limit of its stroke so that the latter part of the stroke acts to release the pressure in the cylinder 4 before valve 7 opens. This happens partly because of the extremely high pressure, 200 atmospheres or over and partly because the gas dissolved in the liquid makes its escape on releasing the pressure. Then the valve 13 is shut and valve 12 opened and auxiliary liquid admitted to the cylinder 11 to cause the piston to expel the contents of the cylinder 4 (now at low pressure) into the container 9. The cycle is then repeated.

The valves 3, 7, 12 and 13 are preferably operated hydraulically by an independent system and in any case their movements may be co-ordinated through the agency of a timing gear in known manner.

Cylinders may be also inverted, the auxiliary fluid cylinder on top.

The arrangement shown however, has the advantage that any gas dissolved in the liquid portion of the material and liberated on reduction of pressure will rise in the cylinder 4 and make its escape to the container 9 before the liquid is pushed out by the return stroke of the piston.

We declare that what we claim is:—

1. A process for obtaining a mixture of solid

- and liquid at substantially atmospheric pressure from a mixture of the same ingredients at high pressure, said high-pressure mixture being the product of a high pressure chemical reaction, consisting in introducing the said mixture without substantial pressure drop into a space, and then allowing it to expand therein by transference of its pressure energy to a non-abrasive auxiliary liquid.
- 5 2. A process for obtaining a mixture of solid and liquid at substantially atmospheric pressure from a mixture of solid and liquid at high pressure, said high-pressure mixture being the product of a high pressure chemical reaction, consisting in filling a confined space with a non-abrasive auxiliary liquid, allowing the mixture of solid and liquid to flow without substantial pressure drop into a second confined space, transferring the pressure from said mixture to said auxiliary liquid and releasing the pressure on said auxiliary liquid.
- 10 3. A process as set forth in claim 6 in which the expulsion of the said material is effected by supplying said auxiliary liquid at a few atmospheres pressure, to the said first confined space.
- 15 4. A process as set forth in claim 6 in which the expulsion of the said material is effected by supplying said auxiliary liquid at a few atmospheres pressure, to the said first confined space and so regulating the rates of supply and expulsion of said liquid that only slow movement occurs.
- 20 5. A process for obtaining a mixture of solid and liquid at substantially atmospheric pressure from a mixture of solid and liquid at high pressure, said high-pressure mixture being the product of a high pressure chemical reaction, consisting in passing said mixture into a confined space without substantial pressure drop, transferring the pressure to a non-abrasive auxiliary

liquid and controlling the rate of passage by regulating the escape of an auxiliary non-abrasive liquid from a second confined space.

6. A process for obtaining a mixture of solid and liquid at substantially atmospheric pressure from a mixture of high pressure solid and liquid, said high-pressure mixture being the product of a high pressure chemical reaction, consisting in passing a non-abrasive auxiliary liquid into and thereby expanding a variable space, herein-after termed the first space, which space is complementary to another variable space, herein-after termed the second space, introducing the mixture of high pressure liquid and solid without substantial pressure drop into the second space thereby slowly expanding it and slowly contracting the first space and ejecting a part of the non-abrasive liquid therefrom, arresting the inflow of the liquid and solid into the second space, allowing the liquid and solid therein to drop to substantially atmospheric pressure by further expansion of the second space, and finally ejecting the liquid and solid from the second space by expanding the first space by passing thereinto non-abrasive liquid.

7. A process for obtaining a mixture of solid and liquid at substantially atmospheric pressure from a mixture of high pressure solid and liquid, said high-pressure mixture being the product of a high pressure chemical reaction, consisting in passing the said material without substantial pressure drop into and thereby expanding a variable space, arresting the inflow of the material into the space, allowing the material therein to drop to substantially atmospheric pressure by further expansion of the space, and finally ejecting the liquid and solid therefrom by contracting the space.
